UNITED STATES PATENT OFFICE.

OTTO THIEME, OF ST. LOUIS, MISSOURI, ASSIGNOR TO MOON-HOPKINS BILLING MACHINE COMPANY, OF ST. LOUIS, MISSOURI, A CORPORATION OF MISSOURI.

LINE-COUNTING ATTACHMENT.

1,163,282.

Specification of Letters Patent.

Patented Dec. 7, 1915.

Application filed November 12, 1913. Serial No. 800,488.

To all whom it may concern:

Be it known that I, OTTO THIEME, a citizen of the United States, residing at St. Louis, Missouri, have invented a certain new and useful Improvement in Line-Counting Attachments, of which the following is a full, clear, and exact description, such as will enable others skilled in the art to which it appertains to make and use the same, reference being had to the accompanying drawings, forming part of this specification, in which—

Figure 1 is a perspective view illustrating a method of attaching my improved counting device to a billing machine, and showing the operating connections thereof. Fig. 2 is a front elevation of the counting device with the bell removed. Fig. 3 is a front elevation with the bell and hoop removed. Fig. 4 is a rear elevation. Fig. 5 is a cross section on line 5—5 of Fig. 4. Fig. 6 is a fragmentary detail.

This invention relates broadly to registers, and specifically to a form of register adapted to be used with writing machines.

It is designed particularly for the purpose of registering the line spacing operations of a typewriting machine or a calculating machine, and for indicating when a predetermined number of such operations have been effected.

The broad purpose of my invention is to provide a counting mechanism capable of registering successive operations of a mechanism, and which is capable of being set variably so as to indicate when any selected predetermined number of operations have been performed, and means for operating such mechanism from various keys of a billing machine.

The particular object of my invention is to provide a counter of the sort described which is accurate and certain in all of its operations, and which is simple and durable in its construction.

Another object of my invention is to provide in such a device an alarm mechanism which will suitably indicate to the operator when the predetermined operations of the machine have been performed.

Another object of my invention is to provide in such a device a means whereby the

counter may be returned to zero or starting position independently of any operation of the machine to which it is applied. 55

A further object of my invention is to provide an improved connecting arrangement whereby the counting mechanism may be operated from any of a plurality of keys independently of operation of the others of such keys adapted to operate the counting mechanism.

Other and further objects of my invention will be obvious from an understanding of the mechanism shown in the drawings. 65

In the use of typewriting machines, billing machines, or computing machines, it is desirable frequently that the operator know when a predetermined number of items has been listed, a predetermined number of amounts inserted in the machine, or a predetermined number of lines has been written. In the modern billing or computing machines, the line spacing operation of the paper upon which the amounts or items are printed is 75 generally effected upon each operation of the machine through suitable mechanism, motor operated, and controlled by a key in the keyboard, commonly known as a "motor key." In some machines, the operation of 80 the line spacing mechanism is also effected in connection with the operation of carriage return mechanism. In my copending application No. 642,888, filed August 7, 1911, I have shown a mechanism wherein the line 85 spacing function is exercised in conjunction with the carriage return operation, and in my copending application No. 701,518, filed June 4, 1912; and the copending application of William Wooley, No. 701,787, filed June 90 5, 1912, are shown a mechanism in which the operation of the motor-operated mechanism of the machine, to wit, the calculating and number printing mechanism, is controlled in conjunction with the carriage return and 95 line spacing mechanism illustrated in the first mentioned application, by means of a single key. The device which I claim as my invention in this application is designed particularly for use in conjunction with any of 100 the mechanisms illustrated and described in the applications above mentioned.

Upon a suitable support 1 is mounted a stud 2 upon which is carried a disk 4 which

is adapted to rotate thereon under the influence of a suitable watch spring 5. The disk 4 is provided with peripheral ratchet teeth 6 and carries projecting toward support 1 a stud 7.

A means for progressively rotating disk 4 is provided and consists of the three armed lever 8 which may be operated from the motor key, carriage return key, or a similar member which causes the line spacing mechanism to become effective. One arm of lever 8 affords attachment for the operating link 20, and a second arm of lever 8 carries feeding pawl 9 which is spring pressed so as normally to engage the ratchet teeth 6. Oscillation of lever 8 against the tension of spring 8^a causes disk 4 to be rotated in a direction counter-clockwise as the parts are shown in Figs. 2 and 3, one tooth or step at each operation. A means is provided for holding disk 4 in any advanced position against the tension of spring 5 and this means consists in the holding pawl 10 which is pivoted on support and is spring pressed so as to engage the ratchet teeth 6. On support 1 is mounted a releasing member in the form of a sliding plate 11, movement of which is controlled by a dog 12 as herein-after explained. Sliding plate 11 carries pins 14, 15 and 16 which project through slots in support 1. Pin 14 lies in the path of stud 7, while pin 16 is adapted to engage the tail end of pawl 10. Pin 15 is a means of attachment for a spring 13, which tends to draw plate 11 to the right as shown in Fig. 2. When sliding plate 11 is in normal position, pin 16 has no effect upon pawl 10, but when sliding plate 11 is slid in a leftward direction pin 16 will be moved so that the latter will cam pawl 10 out of engagement with disk 4.

The feeding pawl 9 is of bell crank shape and a stationary pin 3 co-operates with the rear arm thereof to rock said pawl out of engagement with disk 4 upon the upward or retracting stroke of lever 8. Feeding pawl 9 also has a hook on the rear arm thereof which co-operates with pin 3 to prevent overthrow of lever 8 and disk 4. When pawl 10 is cammed out of engagement with disk 4 said disk will be retained by pawl 9 until said pawl 9 is cammed out of engagement therewith by its contact with pin 3 upon the next retracting movement of lever 8. Upon being thus released by pawl 9, disk 4 will return to normal or starting position under the influence of spring 5, being stopped by the engagement of stud 7 with pin 14.

As illustrated in Fig. 4 sliding plate 11 is provided with notch 11^a and carries projecting pin 11^b. Dog 12 which is spring pressed into engagement with sliding plate 11 is primarily for the purpose of holding sliding plate 11 in its leftward position during

the time that disk 4 is returning to starting position after having been released by leftward movement of plate 11 as just described.

Dog 12 is controlled in its operation by a pin 12^a carried on the third arm of lever 8. When sliding plate 11 is slid leftwardly in the manner hereinabove described, dog 12 drops into notch 11^a and holds said plate 11 in the leftward position, in which position pawl 10 is held out of engagement with disk 4. Upon the subsequent operation of lever 8 pin 12^a co-operating with the rear end of dog 12 lifts the dog out of notch 11^a and permits plate 11 to return to normal position under the influence of spring 13. From this description, it will be seen that during the oscillations of lever 8, disk 4 will be progressively rotated until sliding plate 11 is moved so as to release disk 4 whereupon it returns to normal position.

The means for operating sliding plate 11 to release disk 4, and the means for predetermining the extent to which disk 4 will be rotated before being released consists of the hoop 17 which is adjustably carried upon stud 2. Hoop 17 is provided with small pins 18 which are adapted to engage in any of the ratchet teeth 6, and hoop 17 normally is held in engagement with disk 4 by the pressure of spring 19. Hoop 17 may be adjusted circumferentially with respect to disk 4 by simply lifting it against the pressure of spring 19 and rotating it on stud 2 to the proper extent. By the circumferential adjustment of hoop 17 relative to disk 4 is determined the position relative to pin 15 of a lug 24 projecting radially from hoop 17. Lug 24 projects sufficiently to engage pin 15, and by virtue of such engagement, upon the requisite rotation of disk 4 and hoop 17, slides plate 11 leftwardly in position to retract pawl 10. Thus it will be seen that the farther lug 24 is positioned away from stud 15 in a clockwise direction, when disk 4 is in normal position, the greater will be the extent of rotation permitted disk 4 and the greater the number of operations of the machine necessary to release disk 4 to permit its return to normal. On its periphery, hoop 17 is provided with a dial graduated in space units corresponding to the teeth in disk 4 and numbered to indicate the number of operations which will be permitted before disk 4 will be released. The number on the dial corresponding to the number of operations desired, is positioned at pin 15 or other suitable guide and the proper adjustment of lug 24 thus obtained.

An alarm mechanism of well known form is provided consisting of bell 25 and spring 12^b pressed striking hammer 26. These are mounted on sleeve 2 with pallet 27 extending in the path of a lug 28 carried on hoop 17. Upon the prerequisite rotation of disk 4 and hoop 17, lug 28 engages pallet 27 130

causing hammer 26 to strike bell 25 which furnishes the desired signal to the operator that the predetermined number of operations have been effected.

5 A means is provided for returning the disk to starting position before it reaches the maximum point of rotation for which it is adjusted. It is frequently desired to do this when a total is struck to finish a column 10 of numbers, or on other occasions when it is desired to begin a new column. As shown, the mechanism for thus returning the device consists of the bell crank lever 29 which, when it is swung, by its operating 15 member 30, engages pin 11^a and slides plate 11 into position to cause the release of disk 4. This lever may be operated by means of a suitable connection 30 from a total key or product key of a computing machine, or, 20 of course, from a totally independent key or other means controlled by the operator.

In Fig. 1 is illustrated various operating connections whereby the counter may be operated from various keys in the keyboard 25 of a billing machine. In the illustration 1 represents the frame of the machine in which are mounted the customary printing mechanisms.

32 represents the motor key which operates to throw in the actuating motor so as to actuate the printing mechanism.

34 represents the carriage return key, operation of which as illustrated in my co-pending application No. 642,888, clutches 25 the motor to the carriage return mechanism for the purpose of returning the paper carriage to starting position.

35 represents either a total or a product key, operation of which positions certain 40 mechanisms of the calculating mechanism so that a total or a product will be taken upon a subsequent operation of the motor key.

A shaft 36 is rotatably mounted in the 45 frame 1, and has affixed thereto the crank arm 37. The end of crank arm 37 is pivotally connected to the bar 38 which bar corresponds to the rods 170 or 302 of the total or product keys illustrated in the co-pending application of Hubert Hopkins No. 310,739, and which rod is actuated by operation of key 35. Actuation of key 35, by virtue of the connection with crank arm 37, operates to rotate rod 36. Rod 36 has keyed 50 to it a second crank arm 39 which is connected to connecting link 30. The rotation of shaft 36 by operation of key 35 draws link 30 downward, thereby actuating bell crank lever 29 which in turn shifts plate 11, as above described to return the counter to starting position. The effect is that whenever a total or product is struck the counter will be returned to starting position.

Rotatably mounted upon shaft 36 is a 55 sleeve 40 which carries at one end a crank

arm 41 and at the other a crank arm 42. Crank arm 41 is connected by link 44 and bell crank 45 to motor key 32 in such fashion that operation of the motor key rotates sleeve 40 on shaft 36. Crank arm 42 is connected to operating link 20 in such manner that when sleeve 40 is rotated by operation of motor key 32 operating link 20 will be drawn downward to swing three armed lever 8 and advance the counter one step as hereinbefore described. The result is that upon each operation of motor key 32 the counter 75 will be advanced one step up to the limit for which the counter is set.

The bar 34^a of carriage return key 34 carries a stud 46 which co-operates with the bottom of the slot in the upper portion of a slotted link 47. The lower end of slotted link 47 is connected to operating link 20 in such fashion that when carriage return key 85 34 is depressed operating link 20 will be drawn downward by virtue of engagement of stud 46 with the bottom of the slot in link 47. The slot in link 47 permits of the operation of connection link 20 by motor key 32 90 independently of operation of the carriage return key, as the slot is of sufficient extent to permit link 47 being drawn downward by the operation of sleeve 40 and crank arm 42 without engaging stud 46 to draw down 95 carriage return key 34. As a result of this arrangement of parts, it is obvious that the counter may be advanced by the operation of either motor key 32 or carriage return key 34, and that it may be so operated by 100 either of said keys without such operation affecting the other of said keys. Furthermore, it is obvious that the counter will be released to return to starting position upon the operation of key 35 representing either 105 the total or the product key of a computing machine.

It is frequently the case in taking a total that the total key returns before the motor key returns. The obvious result of this will 110 be to permit link 30 to return upwardly swinging bell crank lever 29 back and thus releasing sliding plate 11 while dog 12 is held out of engagement with sliding plate 11 by pin 12^a which is held elevated so long 115 as the motor key operating link 20 and lever 8 is depressed. Consequently, when sliding plate 11 is thus released, it slides immediately to its extreme position (leftward in Figs. 4 and 6), and releases the retaining 120 pawl 10 which immediately drops into engagement with disk 4 before said disk has returned to starting position. Thus it is 125 obvious that upon the next forward rotation of disk 4, the full number of lines or items for which the mechanism is set will not be counted. As just explained, the reason for this stopping of disk 4 before it returns to starting position is due to the fact that sliding plate 11 is not retained with pin 16 in 130

engagement with pawl 10 a sufficient length of time to permit the full return of disk 4 when the total key is released before the motor key returns to normal position. As 5 a means for preventing such improper action, I provide the restraining pawl 50 having the notch 50^a which is designed to co-operate with a pin 51 carried on sliding plate 11. The rear end of restraining pawl 10 10 50 has a projection 50^b with which pin 12^a co-operates near the end of the downward movement of said pin. A spring 52 tends to press the notch 50^a toward the pin 51. The disposal of pin 51 relative to notch 11^a 15 and the notched portion 50^a of pawl 50 is such that when sliding plate 11 is shifted by the movement of lug 24 with pin 15, the movement of said plate is not sufficient to permit the engagement of pin 51 in notch 20 50^a. However, the movement of sliding plate 11 by bell crank 29 is of greater extent than the movement of plate 11 through the engagement of lug 24 and pin 15, and such movement of sliding plate 11 by bell 25 crank 29 is sufficient to permit the engagement of pin 51 by notch portion 50^a. Therefore, it will be obvious that when a total 30 is taken, the operation will be as follows: Depression of the total key shifts sliding plate 11 by means of link 30 and bell crank lever 29 to an extent sufficient to permit the engagement of pin 51 by pawl 50. The subsequent depression of the motor key, which swings bell crank lever 8, releases restraining 35 pawl 50 from pin 12^a and permits its dropping into engagement with pin 51. Sliding plate 11 is thus held by restraining pawl 50, even after its release by bell crank 29, until restraining pawl 50 is cammed out 40 of engagement with pin 51 by the pin 11^a upon its downward movement consequent upon the return of the motor key. Thus it is obvious that dog 12 will hold sliding plate 11 to permit the return of disk 4 45 whenever the motor key returns to normal position before the total key, and that restraining pawl 50 will so restrain sliding plate 11 whenever the total key has been operated and returns before dog 12 is released 50 by the return of the motor key. Such operation insures the invariable return to starting position of disk 4.

From the foregoing, it is obvious that my improved form of register is adapted to be 55 adjusted so as to register any predetermined number of operations, and when such predetermined number of operations has been effected to return to zero position automatically. Furthermore, that the register may be used both as a line counter and as an item counter, being advanced at each operation of the motor key, and being returned to zero or starting position upon operation of the total key.

65. I am aware that modifications may be

made in the structure disclosed without departing from the scope of what I claim to be my invention, and I intend that my invention shall be construed to comprehend all such structural variations.

What I claim is:

1. In a counter, the combination of a rotatable disk, an actuating lever, a pawl operable by said lever to rotate said disk in one direction, a retaining pawl adapted to 70 retain said disk in position after such rotation, a releasing member adapted to retract said pawl to free said disk, and means operated from said actuating lever for operating said releasing means.

2. In a counter, the combination of a rotatable disk, an actuating means adapted to rotate said disk in one direction, a retaining member co-operating with said disk to hold it in position when so rotated, a releasing member adapted to free said disk from said retaining member, means for returning the disk to starting position, means for holding the releasing member in co-operation with the retaining member during the return of 85 said disk to starting position, and means operated by said actuating means for freeing said releasing means from said holding means.

3. In a counter, the combination of a rotatable disk, actuating means for rotating it in one direction, retaining means for retaining said disk in position after being so rotated, means for returning said disk to starting position, means operable by said 95 actuating means for releasing said disk from said retaining means, and an independently operable means for releasing said disk from said retaining means to permit its return to starting position.

4. In a counter, the combination of a rotatable disk, means for gradiently rotating the same in one direction, means for rotating the disk in the opposite direction, a retaining member co-operating with said disk, 100 a sliding plate adapted to operate said retaining member and operable independently of the same and means operable from said disk for operating said sliding plate.

5. In a counter, the combination of a rotatable disk, actuating means for gradiently rotating the same in one direction, means for returning the disk in the opposite direction, means for retaining the disk in advanced position, releasing means for freeing the disk from said retaining means, and means releasable by said actuating means for maintaining said releasing means in effective position during the return of said disk to starting position.

6. In a counter, the combination of a disk, means for gradiently advancing the same in one direction, independently operable means adapted to release the disk to permit its return to starting position, and 120 125

means operable to permit the full return of said disk when both of said means are operating simultaneously.

7. In a counter, the combination of a movable member, an oppositely movable actuating member for gradiently advancing the same, retaining means for holding the member in advanced position, releasing means for releasing said movable member from said retaining means to permit its return to normal, means for operating said releasing means, and holding means for retaining said releasing means in operative position to permit the movable member to return to normal, said holding means being operable by said actuating means to permit the retaining means becoming effective upon the movable member.
8. In a counter, the combination of a movable member, an oppositely movable actuating means for gradiently advancing the

same, retaining means for retaining the movable member in advanced position, releasing means for releasing the movable member from the retaining means, a holding member for holding the releasing means in operative position, said holding member being rendered inoperative on the forward movement of the actuating means, an independent holding member operable upon the releasing member, said holding member being rendered inoperative upon the reverse movement of the actuating means, and means for moving the releasing means for the purpose described.

In testimony whereof I hereunto affix my signature in the presence of two witnesses, this 3d day of November, 1913.

OTTO THIEME.
